METHOD AND APPARATUS FOR DISCHARGING LIQUIDS FROM IMMERSSED VESSELS

Augustine John Tucker, 911 S. Post Oak Lane,
Houston, Tex.

Filed July 20, 1965, Ser. No. 473,404
14 Claims. (Cl. 114—52)

This invention relates to a method and system or apparatus for discharging liquids from an immersed vessel or tank. More particularly, this invention relates to a method and apparatus or system for controlling the inside-outside pressure differential in a tank or a vessel while a liquid is being removed therefrom and while the vessel is immersed in an immersion medium such as a liquid. This removal of the liquid may be, for example, the removal of water from a submerged tank or vessel during a salvage operation wherein the water is displaced from the submerged tank or vessel to gain buoyancy.

In the process of raising tanks or vessels which are completely sunk or immersed, it is common practice for salvors to install air connections to the tank spaces, apply air pressure to blow the water out and gain buoyant lift to bring the hull to the surface. The degree or amount of air pressure required to accomplish this is proportional to the water depth, with approximately one-half pound of pressure being required to overcome the hydrostatic head pressure or outside pressure of each foot of water depth.

Marine hulls are usually designed for an internal stress sufficient to withstand the hydrostatic head pressure of the hull depth plus some margin of safety. When air pressures are introduced into the tank when the tank is submerged, the permissible amount of inside pressure must be controlled such that the inside-outside pressure differential does not exceed this designed bursting capacity, closely restricted to the safety factor.

Even though the hull is submerged to a considerable depth, high air pressures can be applied to the inside of the tank if the loading is no greater than the differential of pressure between the outside hydrostatic head pressure and the inside pressure. The tank will be de-watered through the valve in the bottom of the tank or vessel because the liquid or water contained in the tank will be reposed in the bottom and the air will be collecting on the top, such that the pressure of the water plus the pressure of the air is greater than the outside pressure of the water alone. When all of the water has been purged or displaced from the tank, any excess air pressure will be relieved by venting out the bottom and the system will be in balance.

The precise control of the balance through the de-watering cycle is very difficult. If air pressure over the safe pressure differential is applied while there is still a water level in the tank, the hull will burst because the water cannot be pressed out of the bottom valve fast enough to open a relief passage for the pressure build-up. Therefore, cautious marine salvors have in some instances installed spring loaded or weight loaded relief valves in the top of the tank to blow off the excess air pressure. However, these valves are also under the hydrostatic head loading or outside water pressure, and are not wholly reliable within the small tolerances of pressure allowed. Moreover, they often collect trash and rags, and hence may become stuck in the open position to thereby vent all of the air pressure from the tank with resultant disaster if the tank has been partially raised.

It is, therefore, an objective of this invention to provide an improved method and system for relieving the pressure inside the tank when it exceeds the predetermined level, which method and system is reliable because

there are no moving parts and because it will control pressure differential with precision regardless of water depth.

Briefly stated, this invention is for a method of discharging liquids from a liquid containing vessel immersed in an immersing medium, such as water, which comprises the steps of introducing a pressurized fluid, such as air, into the vessel at a pressure differential sufficient to displace the liquid therefrom. The liquid in the tank, such as water, is displaced therefrom by application of the pressurized fluid. When the pressure differential between the inside and outside of the vessel or tank exceeds a predetermined level, (i.e., the safe internal stress capacity of the vessel) the inside pressure is relieved therefrom by venting the pressurized fluid from a first point located inside the vessel and above the liquid level therein to a second point located exteriorly of the vessel and spaced below the first point a distance which is sufficient to cause the venting to occur when the pressure differential exceeds the predetermined level.

The system of this invention is adapted for discharging a liquid from a liquid containing vessel immersed in an immersing medium and includes means for introducing a pressurized fluid into the vessel to displace the liquid therefrom. Outlet means are also provided for discharging liquid from the vessel. In addition, there is provided conduit means associated with the vessel for relieving the pressure inside the vessel when the pressure differential inside and outside the vessel exceeds a predetermined amount. This conduit means communicates between a first point located inside the vessel and above the liquid level therein and to a second point located exteriorly of the vessel and spaced below the liquid level inside the vessel a distance which is adapted to maintain the predetermined pressure differential.

It is to be understood that this invention is particularly adaptable to raising or salvaging submerged or sunken vessels, as will be explained hereinafter, but may also have utility in unloading liquid cargos and ballast from vessels and the like.

Reference to the figures will further explain the invention wherein like numerals refer to like parts and in which:

FIG. 1 is a schematic cross-sectional view of a tank showing the system of this invention installed therein.

FIG. 2 is a schematic cross-sectional view of a ship hull or vessel having a dual system for carrying out the liquid discharging as taught by this invention.

FIGS. 3A, 3B, and 3C are schematic cross-sectional views showing a tank having the invention system installed therein, which tank is adaptable for rotation in the water or submerging medium, and showing three different positions during the rotation.

FIG. 4 is another embodiment of the invention showing a tank in schematic cross-sectional view, which tank likewise adaptable for rotation or turning in the water immersing medium.

Referring now to FIG. 1, a closed tank or vessel 11 shown submerged in an immersing medium such as water and is partially filled with a fluid, such as water, at water level 12 therein.

Means are provided for dispersing the water from vessel 11 which means conveniently takes the form of valve 13 which communicates with the exterior of tank 11 or vessel 11 and which is operated by valve handle 14 from above. Upon opening of valve 13, water inside vessel 11 may be displaced therethrough to the exterior of the vessel 11 upon application of fluid pressure to valve 13.

The top portion of vessel 11 is provided with means for supplying pressurized fluid such as pressurized air through valve 15 which means takes the form of air line 15 which

connected to air valve 16, which communicates with T-fitting 17, which communicates with the air space in the top vessel 11 above water level 12 therein. T-fitting 17 has connected thereto blow-off pipe 18 which likewise communicates with the air space above water level 12 in vessel 11 through T-fitting 17. It will be noted that pipe 18 extends downwardly along the outside of vessel 11 and terminates at a point approximately even with the bottom of vessel 11 and has standing therein a column of water, the top level of which corresponds with water level 12 in vessel 11. It will be observed that pipe 18 may be described as an open ended conduit, the top end of which communicates with a point located inside vessel 11 and above water level 12 therein and that the bottom end of pipe 18 communicates with a point located exteriorly of vessel 11 and below water level 12 in the vessel 11.

When pipe 18 is installed as shown in FIG. 1, there is a balanced column of water plus air pressure on the inside of the pipe just as there is on the inside of tank or vessel 11. As long as this column of water is just sufficient for de-watering vessel 11, the level of the water and pipe 18 will stand at an equal level therewith. However, if there is an excess of air pressure applied to vessel 11 above a predetermined level, pipe 18 will be purged of the column of water and air pressure inside vessel 11 will be vented therethrough. The predetermined amount of pressure differential between the inside of vessel 11 and the outside is determined by the length of pipe 18. Since pipe 18 is open at the bottom and the surface area on the top of the water column in pipe 18 is the same as the cross-sectional area at the lower end of pipe 18, the pipe 18 will vent instantaneously when the air pressure exceeds the predetermined differential.

As explained above, most tanks or vessels have an internal stress capacity which is large enough to accommodate the depth of the vessel taking into consideration the specific gravity of the liquid which may be placed therein. Hence, the predetermined amount of the differential which is established by pipe 18 is determined by the vertical dimension of the blow-off pipe and the density of the fluid contained therein.

Pipe 18 can be dimensioned to something greater or less than the tank height. If it is less than the height of the tank, a predetermined amount of fluid can be removed from the tank and when this level is reached, the blow-off will stop the de-watering action at the level of the lower end of pipe 18. As the end of pipe 18 is made to extend deeper than vessel 11, and assuming the vessel has this degree of bursting stress, vessel 11 can be sunk into deeper water without ingesting water ballast. This sometimes occurs when capsized vessels are being rolled over while afloat on the surface and the ingestion of any water thereto would circumvent all of the calculations if the low tide tank took on any ballast during the roll.

Vessels, such as vessel 11, which have sunk to the bottom of a body of water, usually settle into the sand and mud bottom. In order to remove such a vessel when it is settled to the bottom, additional "breakaway-lift" must be applied in excess of the normal buoyancy required to lift just the weight of the vessel alone. However, once the vessel has broken away from the bottom, there is immediately developed an excess of positive buoyancy which uses the vessel to rise to the surface very rapidly. The faster the vessel is submerged, the greater will be the pressure required to displace the water in the tank. As vessel 11 rises and the hydrostatic head or outside pressure decreases, the air in the tank must be vented continuously or an excess of internal pressure will exist over permissible or safe inside-outside pressure differential. Vessel 11 still has a water level therein above valve 13 in the upward movement of vessel 11 begins, the air not escape through the bottom valve 13. Even though de-watering process accelerates as the outside head pressure decreases, the water will not flow fast enough

through valve 13 to clear the passage for the relief of air under ordinary circumstances and without the present invention.

However, with pipe 18 installed with adequate cross-section dimension as shown, the relief of air pressure inside vessel 11 is immediate, continuous and paced to the speed of the rising vessel. The relief is continuous because pipe 18 is in the form of an open ended conduit without valve closings controlling the movement of fluids therethrough. The bursting capacity of vessel 11 is never exceeded since purging or venting of air pressure therewith would occur when air pressure exceeded the predetermined level, i.e., the predetermined level being determined by the length of pipe 18. At the same time, there is no danger that the air retained inside vessel 11 will be permitted to escape therefrom by a faulty air valve, which sometimes occurs with prior art systems. If that should occur, then vessel 11 would settle again to the bottom. This catastrophe cannot occur with this invention because there is no air valve which can be stuck in the open position.

FIG. 2 shows the system of this invention installed as a permanent system in a ship or vessel hull 22 so that air pressure may be used to de-water ballast tanks or discharge liquid cargos with no risk of bursting the tanks. FIG. 2 shows that hull 22 is divided into two separate and enclosed compartments, each of which has means for supplying pressurized air thereto in the form of air valve 23 which is connected to an appropriate pressurized air source. In addition, each of the compartments is provided near the bottom with water valve 24 which is adapted to be manipulated by valve handle 25 from above. Valves 24 control the passage of liquids through internal conduits 26, the internal ends of which are in communication with the lower end of the compartments and the external ends of which are in communication with the outside of hull 22. In addition, each of the compartments is provided with a blow-off pipe 27, the upper end of which is in communication with the upper end of the compartment and the lower end of which is in communication with the exterior of hull 22. The operations of each of the systems shown in FIG. 2 are exactly the same as that shown in FIG. 1. In other words, pipes 27 correspond to blow-off pipe 18 in FIG. 1. In addition, valves 24 correspond with valve 13 in FIG. 1, and air valves 23 correspond with air valve 16.

When it is desirable to remove the liquid from the compartments in hull 22 air pressure is applied through valve 23 to the air space above the liquid level in the compartment of hull 22 which is being unloaded. This air pressure causes the evacuation or displacement of the liquid therefrom through conduit 26 through valve 24 to the exterior of hull 22. However, when air pressure inside of the compartment exceeds the predetermined level as established by the length of pipe 27 then the air pressure will be discharged through pipe 27 to the exterior of the vessel. Hence, there is a built-in safety factor which does not permit the internal air pressure to exceed the bursting capacity of the vessel. The system can be used to discharge liquid cargos or to discharge water which has been taken on as ballast without danger of bursting the hull of the vessel.

FIGS. 3A, 3B and 3C show another embodiment of the present invention. In this embodiment, vessel 31 is provided with two generally L-shaped and open ended conduit means in the form of blow-off pipe 32 which is connected to T-fitting 33 which is attached to the top portion of vessel 31. Pipe 32 extends downwardly along the side of vessel 31 and underneath vessel 31. Hence, it may be said that pipe 32 communicates with a point inside the vessel 31 and above water level 34 therein to a point exterior of vessel 31 and below water level 34 therein.

Vessel 31 is also provided with another open ended conduit means in the form of discharge pipe 35, the lower end of which is in communication with the lower portion

of vessel 31 and extends upwardly through vessel 31 and at right angles over the top of vessel 31. Air pressure is applied to vessel 31 via air line 36 through air valve 37. The operation of the vessel shown in FIG. 3A is in all respects the same as that in FIG. 1. When air pressure inside vessel 31 exceeds the predetermined level determined by the vertical height of the water column in pipe 32 air is vented from the vessel 31 through pipe 32. Meanwhile, the liquid or water in vessel 31 is displaced therefrom through pipe 35 which communicates with the outside of vessel 31 as explained above. Since both pipe 32 and pipe 35 are open ended conduits there is no danger of the passages becoming fouled or clogged as with certain mechanical valves used in the prior art. This embodiment is particularly useful for righting or rolling capsized vessels. FIGS. 3B and 3C show the vessel 31 being rotated to the inverted position which might sometimes occur during salvage procedures. When the 180° rotation is completed as shown in FIG. 3C, pipes 35 and 32 have merely exchanged functions with pipe 35 now acting as the blow-off pipe in case of excess pressure and with pipe 32 acting as the de-watering pipe.

One advantage of this particular embodiment is that the air pocket inside of vessel 31 is retained during the roll. At the same time, if vessel 31 should rise during this rotation it will be relieved of excess air pressures through whichever one of the pipes is then in a position to act as the venting pipe.

However, it will be noted that there may be a temporary increase in the differential pressure inside and outside the vessel, which increase is equal to the difference between the diagonal distance between the pipe ends and the vertical height of the tank during the roll. If this can be tolerated, either or both of the systems will function during the rotation.

If vessel 31 does not have sufficient stress capacity to tolerate this increased pressure differential during rolling, then the outside legs of the de-watering pipe and the blow-off pipe can be shortened as shown in FIG. 4.

There tank or vessel 31 is shown having dual conduits in the form of pipes 41 and 42 installed therein. Pipe 41 generally corresponds with pipe 35 shown in FIG. 3A and pipe 42 generally corresponds with pipe 32 shown in FIG. 3A. However, by having the shortened legs as shown, during the roll of vessel 31 as described with respect to FIGS. 3A, 3B and 3C, the internal stress capacity of the vessel 31 will not be exceeded since vertical dimensions h are equal to the height of tank 31 when in a horizontal position. Hence, the internal stress capacity of vessel 31 would never be exceeded during the rolling operation assuming that the stress capacity was equal to the hull depth or the vessel depth in the horizontal position. Here again, the air inside of vessel 31 is entrapped during the roll, yet there is positive assurance that air pressure inside vessel 31 will not exceed the bursting capacity of the vessel. The vertical dimensions of the water columns in pipes 41 and 42 could never exceed the height of the tank, which is the distance h and, hence, the bursting capacity would never be exceeded.

It will be observed that the art has been provided with a new and novel system and method for discharging liquids from vessels in a safe and convenient manner without danger of bursting the vessel. Moreover, the system and method is adaptable for salvaging submerged tanks with similar assurance that the vessels will not burst during the salvaging operation.

Modifications may be made in the invention as particularly described without departing from the scope of the invention. Accordingly, the foregoing description is to be construed illustratively only and is not to be construed as a limitation upon the invention as defined in the following claims.

What is claimed is:

1. The method of discharging liquid from a liquid

containing vessel immersed in an immersing medium, said method comprising the steps of:

introducing a pressurized fluid into the vessel at a pressure sufficient to displace the liquid therefrom; displacing the liquid from the vessel by application of the pressurized fluid; and relieving the pressure inside the vessel when the pressure differential inside and outside the vessel exceeds a predetermined level by venting the pressurized fluid from a first point located inside the vessel and above the liquid level therein to a second point located exteriorly of the vessel and spaced below the first point a distance which is sufficient to cause the venting to occur when the pressure differential exceeds the predetermined level.

2. The method as claimed in claim 1 wherein: the pressurized fluid has a lower specific gravity than the liquid being displaced and is immiscible therewith.

3. The method of discharging water from a water containing vessel immersed in a body of water, comprising the steps of:

introducing a pressurized gas into the vessel at a pressure sufficient to displace the liquid therefrom; displacing the water from the vessel by application of the pressurized gas; and relieving the pressure inside the vessel when the pressure differential inside the vessel exceeds the pressure outside the vessel by a predetermined amount by venting the pressurized gas from the vessel through a path starting at a first point located inside the vessel and above the water level therein and ending at a second point located exteriorly of the vessel and spaced below the first point and below the liquid level inside the vessel a distance which is sufficient to cause the venting to occur when the pressure differential exceeds the predetermined amount.

4. The method of raising a liquid containing vessel immersed in a body of liquid, comprising the steps of:

applying pressurized gas to the inside of the vessel; forcing the liquid from the vessel by application of the pressurized gas; and relieving the pressure inside the vessel as the vessel rises causing the pressure differential inside and outside the vessel to exceed a predetermined level by venting the gas from a first point located inside the vessel and above the liquid level therein to a second point located exteriorly of the vessel and below the liquid level therein.

5. The method of raising an enclosed liquid containing vessel immersed in a body of liquid, comprising the steps of:

applying pressurized air to the inside of the vessel at a sufficient pressure to displace the liquid therefrom; displacing the liquid from the vessel by the application of the pressurized air; and relieving the pressure inside the vessel when the pressure differential between the inside of the vessel and outside of the vessel exceeds the safe internal stress capacity of the vessel by venting air from a first point located inside the vessel and above the liquid level therein to a second point located exteriorly of the vessel and below the liquid level in the vessel.

6. In a system for discharging a liquid from a liquid containing vessel immersed in an immersing medium, said system comprising:

means for introducing a pressurized fluid into the vessel to displace the liquid therefrom; outlet means for discharging liquid from the vessel; and conduit means associated with the vessel for relieving the pressure inside the vessel when the pressure differential inside and outside the vessel exceeds a pre-

- determined amount, with the conduit means communicating between a first point located inside the vessel and above the liquid level therein and a second point located exteriorly of the vessel and spaced below the liquid level inside the vessel a distance which is adapted to maintain the predetermined pressure differential.
7. The system as claimed in claim 6 wherein:
the means for introducing a pressurized fluid into the vessel is adapted to introduce a pressurized gas.
8. In a system for discharging a liquid from a liquid containing vessel immersed in an immersing medium, the system comprising:
means for introducing a pressurized gas into the vessel at sufficient pressure to displace the liquid therefrom; 15
outlet means for discharging liquid from the vessel upon application of the pressurized gas; and
pressure relieving means associated with the vessel for relieving the pressure inside the vessel when the pressure inside the vessel exceeds the pressure outside the vessel by a predetermined amount, the pressure relieving means including open ended conduit means communicating between a first point located inside the vessel and above the fluid level therein and a second point located exteriorly of the vessel 20 and spaced below the liquid level inside the vessel a distance which is adapted to maintain the predetermined pressure differential.
9. The system claimed in claim 8 wherein:
the outlet means for discharging liquid from the vessel 30 includes a conduit communicating from a third point inside the vessel and near the bottom thereof to a fourth point located outside the vessel.
10. The system as claimed in claim 8 wherein:
the open ended conduit means is adapted to normally 35 contain a column of liquid therein, the top level of which is generally level with the fluid level inside the vessel, which liquid column is blown out when the inside-outside pressure differential exceeds the predetermined amount.
11. In a system for discharging a liquid from an enclosed liquid containing vessel immersed in a liquid, the system comprising:
means for introducing a pressurized gas into the vessel at sufficient pressure to displace the liquid therefrom; 45
a first generally L-shaped and open ended conduit communicating with the inside of the vessel at a point near the top side thereof and extending downwardly therefrom and under the vessel;
a second generally L-shaped and open ended conduit communicating with the inside of the vessel at another point near the bottom side thereof and extending upwardly therefrom and over the vessel; 50
whereby the first conduit acts as the liquid dispensing outlet and the second conduit acts as the excess pres-

10

25

40

50

55

sure relief outlet in the upright position and said conduits exchange functions when the vessel is inverted.

12. A vessel adapted for ready salvage after having been submerged by flooding with water, comprising:
an enclosed tank;
means for applying pressurized gas to the inside of the tank at a sufficient pressure to displace the water therefrom;
means for discharging water from the tank upon application of the pressurized gas; and
open ended conduit means communicating from a first point located inside the tank and above the water level therein to a second point located outside the tank and below the liquid level in the tank, with the distance below being selected to maintain a predetermined pressure differential between the inside and outside of the tank, whereby pressurized gas is discharged from the tank through the conduit means when the inside and outside pressure differential exceeds the predetermined level.
13. A vessel adapted for ready salvage after having been submerged by flooding with water, comprising:
a plurality of enclosed tanks, each of said tanks having:
means for applying pressurized air to the inside thereof at a pressure sufficient to displace the water therefrom;
means for discharging water therefrom upon application of the pressurized air; and
open ended conduit means communicating between a first point located inside the tank and above the water level therein and a second point located outside the tank and below the water level therein, with the distance below being selected to maintain a predetermined pressure differential between the inside and the outside of the tank, whereby pressurized air is discharged from the tank through the conduit means when the inside and outside pressure differential exceeds a predetermined level.

14. The vessel as claimed in claim 12 wherein:
each of the conduit means is adapted to normally have a column of water standing therein, the top level of which is generally level with the water level in the tank associated therewith, which water column is blown out when the inside-outside pressure differential exceeds the predetermined amount.
